United States Patent Office

Des. 174,712
Patented May 10, 1955

174,712

DRESS

Karen Stark, New York, N. Y.

Application December 20, 1954, Serial No. 33,617

Term of patent 3½ years

(Cl. D3—26)

Fig. 1.

Fig. 2.

To all whom it may concern:

Be it known that I, Karen Stark, a citizen of the United States, residing in New York city, in the county of New York and State of New York, have invented a new, original, and ornamental Design for a Dress, of which the following is a specification, reference being had to the accompanying drawing, forming part thereof.

I claim:

The ornamental design for a dress, substantially as shown.
